UNITED STATES PATENT OFFICE.

SAMUEL B. BYNUM, OF JACKSON, TENNESSEE, ASSIGNOR OF ONE-FOURTH TO WILLIAM F. LAMB, ONE-EIGHTH TO JOHN P. MALLORY, AND ONE-EIGHTH TO CLARENCE E. PIGFORD, OF JACKSON, TENNESSEE.

SPRING-MOTOR.

No. 873,499.

Specification of Letters Patent.

Patented Dec. 10, 1907.

Application filed December 21, 1906. Serial No. 348,931.

To all whom it may concern:

Be it known that I, SAMUEL B. BYNUM, a citizen of the United States, residing at Jackson, in the county of Madison and State of 5 Tennessee, have invented certain new and useful Improvements in Spring-Motors, of which the following is a specification, reference being had therein to the accompanying drawing.

10 My invention relates to improvements in controlling devices for motors particularly spring motors, and it consists of the novel construction and combination of parts hereinafter described and claimed.

15 The object of the invention is to provide a regulating or controlling device of this character which will be simple and practical in construction and convenient to operate, and by means of which the motor may be instantaneously stopped or started and made to run 20 at any desired speed.

The above and other objects are attained in the preferred embodiment of the invention illustrated in the drawings, in which

25 Figure 1 is a detailed vertical section through a casing of a spring motor showing my improved controlling or governing device applied to the latter and Fig. 2 is a detailed perspective of a portion of the device.

30 In the drawings 1 denotes a portion of a casing or covering of a spring motor 2 having a frame 3 and a main drive shaft 4. On the latter is fixed a beveled gear 5 which meshes with a beveled pinion 6 fixed upon the lower 35 end of a sleeve 7 arranged for sliding movement on the governor shaft 8. This shaft has its upper end mounted in a suitable bearing upon the casing 1 and its lower end mounted in a bearing upon the frame 3.

40 The sliding sleeve 7 is connected to a stationary collar 9 adjustably fixed upon the upper portion of the shaft 8, by springs 10 which carry centrifugal weights 11. These weights fly outwardly when the governor is rotated 45 and bow the springs 10 so that the sleeve 7 is drawn upwardly on the shaft and the pinion 6 is thereby lifted out of mesh with the gear 5 which rotates it. The sliding sleeve 7 also carries a brake disk 12 arranged immedi-

50 ately above the pinion and adapted to co-act with two levers 13, 14 arranged upon the frame 3. The lever 14 is adapted to engage the upper face of said disk while the lever 13 is adapted to engage the lower face of the 55 same and comprises a body of right-angular

form pivoted intermediate its ends upon a bracket 15 and having one of its ends 16 projecting upwardly to provide a handle and its end 17 projecting inwardly so that it may be swung up under the disk 12 to engage and elevate the latter and thereby lift the pinion 6 out of mesh with the gear 5. The lever is thus operated when it is desired to speed the motor since the governor is thereby thrown out of operation and the motor is allowed to 60 run free. The lever 13 may also be used as a brake for instantly stopping the motor, by first adjusting the lever 14, as presently explained, so that the disk 12 cannot be raised a distance sufficient to move the pinion 6 out 65 of mesh with the gear 5 and then operating lever 13 so that its end 17 presses the disk against the lever 14.

The lever 14 is pivoted intermediate its ends to a post 18 upon the frame 3 and has its inner end offset and apertured to receive a friction head or stud 19 adapted to bear against the upper surface of the brake disk 12. The opposite end 20 of the lever 14 is adapted to be engaged and forced upwardly 70 by an adjusting screw 21 arranged in the frame 3 and having at its lower end a milled head between which and the frame is provided a tension spring 22. When the screw 21 is moved upwardly the friction head 19 of 75 the brake lever is forced downwardly upon the brake disk 12 to check the rotation of the latter and hence the speed of the motor. The controlling lever 14 may also be operated by a spring lever 23 pivoted intermediate its ends at 24 on the frame 3 and having a handle 25 at one end and a resilient tongue 26 at its other. This tongue 26 is adapted to engage and slide upon the straight upper edge 27 of the lever 14 and to swing over the 80 pivot or fulcrum of the latter. Said tongue is sufficiently resilient to force either end of the lever 14 downwardly when it is moved upon either side of the pivot or fulcrum post 18. When the tongue 26 is moved outwardly toward the end 20 of the lever 14 the friction head 19 is elevated from the brake disk, and when moved inwardly said head 19 is forced downwardly to check the rotation 85 of the governor.

Having thus described my invention what I claim is:

1. In a spring motor, the combination with a shaft, of a governor shaft, a brake disk slidable on the latter, a gear carried by said disk, 110

a gear on the motor shaft to mesh with the first mentioned one, springs fixed at one end to the governor shaft and at the other end to said brake disk, weights upon said springs, 5 and means for elevating the brake disk to throw its gear out of mesh with the gear on the motor shaft.

2. In a spring motor, the combination with a shaft, of a governor shaft, a brake disk 10 slideable on the latter, a gear carried by said disk, a gear on the motor shaft to mesh with the first mentioned one, springs fixed at one end to the governor shaft and at the other end to said brake disk, weights upon said springs, 15 and a lever for elevating the brake disk to throw its gear out of mesh with the gear on the motor shaft.

3. In a spring motor, the combination with a shaft, of a governor shaft, a brake disk 20 slideable on the latter, a gear carried by said disk, a gear on the motor shaft to mesh with the first mentioned one, springs fixed at one end to the governor shaft and at the other end to said brake disk, weights upon said springs, a

brake lever to co-act with the brake disk, 25 means for adjusting said brake lever and another lever for engagement with the opposite side of the brake disk for the purpose specified.

4. In a motor, the combination with a shaft, of a governor shaft a gear slidably arranged upon the governor shaft, a centrifugally acting device between said gear and said governor shaft; a gear upon the motor shaft adapted to be engaged by the gear on the governor shaft and a lever pivoted intermediate its ends and having one end forming a handle and its other end adapted to lift the gear on the governor shaft out of mesh with the gear on the motor shaft, substantially as 35 described.

In testimony whereof I hereunto affix my signature in presence of two witnesses.

SAMUEL B. BYNUM.
